UNITED STATES PATENT OFFICE

124,233

DESIGN FOR A CALENDAR NOTEBOOK

Walter Lampl, New York, N. Y.

Application October 15, 1940, Serial No. 95,858

Term of patent 14 years

To all whom it may concern:

Be it known that I, Walter Lampl, a citizen of the United States, residing at New York, county of New York and State of New York, have invented a new, original, and ornamental Design for Calendar Notebooks, of which the following is a specification, reference being had to the accompanying drawing, forming a part thereof.

Figure 1 is a top plan view of a calendar notebook in a closed position showing my new design;

Figure 2 is a plan view of the same in open position;

Figure 3 is an edge elevational view of the disclosure in Figure 1; and

Figure 4 is a fragmentary plan view of the top of the cover of the calendar notebook on an enlarged scale for purposes of bringing out more clearly the details of ornamentation.

The numerals shown on Figures 1 and 4 are for purposes of illustration only.

I claim:

The ornamental design for a calendar notebook, as shown and described.

WALTER LAMPL.
